COIN SELECTOR

Otto A. Hokanson, Snyder, N. Y., assignor to The
Rudolph Wurlitzer Company, North Tonawanda, N. Y., a corporation of Ohio

Application December 6, 1945, Serial No. 633,145

4 Claims. (Cl. 194—102)

1

The present invention relates to coin selectors, and more particularly to an improved coin selector which is so constructed as to readily facilitate cleaning and repair.

Coin selectors or slug rejectors are not uncommonly located in such places as to accumulate dust and dirt, and not infrequently coin selectors are also subject to the abuse of certain individuals who stuff paper and extraneous matter into the coin selectors. Where the coin selector has accumulated dirt and foreign matter, it is necessary to either remove the selector or to take the selector apart so that the interior may be cleaned and all foreign matter removed. In certain locations coin selectors frequently accumulate grime, grease and dust which must be cleaned off all of the moving parts of the selector in order to place the selector in proper operating condition. Coin selectors are designed to have certain operating characteristics which usually involve the relative speed of the passage of a coin through certain coin passages. Any change of the proper speed of the passage of the coin due to increased friction resulting from unclean surfaces accordingly results in improper operation. In the past it has been extremely difficult to properly clean the interior of coin selectors because of the type of construction employed.

In order to readily facilitate such cleaning, preferably by means of a brush and a detergent, it would be desirable to provide such structure that convenient access may be had to both of the interior walls of a coin selector. This may be accomplished in accordance with the present invention by providing for the selective manual movement of one of the walls away from a stationary or supporting wall. By so moving the wall through an angle of at least ninety degrees or substantially that amount it is possible to clean all interior surfaces of the coin selector.

It, therefore, is an object of the present invention to provide an improved type of coin selector which is particularly suited for servicing and cleaning the interior.

It is another object of the present invention to provide an improved coin selector in which a normally stationary but movable wall and a movable gate are each movable away from a co-operating wall for cleaning purposes.

Another object of the present invention is to provide an improved coin selector having an improved type of rebound anvil which is positive in operation and which does not readily accumulate dirt and foreign matter.

2

Still another object of the present invention is to provide an improved coin selector having adjacent its entrance means for testing the weight of the coin.

5 Still another object of the present invention is to provide an improved coin selector having a plurality of testing devices therein acting upon a coin in particular order to provide the desired discrimination between acceptable and non-acceptable coins.

Other and further objects of the present invention subsequently will become apparent by reference to the following description taken in conjunction with the accompanying drawings 15 wherein.

Figure 1 is a side view of one type of coin selector constructed in accordance with the principles of the present invention;

20 Figure 2 is an end view of the coin selector shown in Figure 1;

Figure 3 is a perspective view showing the coin selector of Figures 1 and 2 opened for cleaning and servicing;

25 Figure 4 is a perspective view of the back side or the exterior of the fixed wall of the selector when the scavenger lever has been actuated;

Figure 5 is a detailed view of one element of the selector shown in the preceding figures;

30 Figures 6 is a front view of another coin selector constructed in accordance with the present invention;

Figure 7 is an end view of the selector shown in Figure 6;

35 Figure 8 is a perspective view showing the selector of Figures 6 and 7 when opened for cleaning and servicing; and

Figure 9 is a perspective view of the coin selector as seen from the opposite direction when closed.

40 The slug rejector shown in Figures 1 to 5 has a stationary wall 11 and end walls 12 and 13 which may be formed integrally with the stationary wall from a single sheet of material. A cooperating parallel wall 14 is provided so that suitable coin runways and passages may be formed between the two walls 11 and 14. The one end wall 12 is provided with a pair of struck out ears 15 and 16 which are arranged to support pivotally one edge of the cooperating side wall 14. The side wall 14 is provided with struck out lugs or ears 17 and 18 which are arranged generally parallel to the ears 15 and 16. A suitable pin 19 is provided to form the hinged connection between the wall 14 and the end wall 50 12. The other edge of the wall 14 is provided

55 12. The other edge of the wall 14 is provided

with a notched portion 21 which cooperates with an inwardly struck guide portion 22 so that the left edge of the wall 14 as shown in Figure 1 is properly positioned with respect to the end wall 13 and so that the inner surface of the movable wall 14 is properly oriented with respect to the inner surface of the fixed wall 11. The wall 14 normally is retained in position by a spring biased latch member 23 which is provided with a finger grip portion 24. This latch member biased by the spring 20 may be disengaged from the guide portion of the latched strike 22 to permit the movable wall 14 to be moved outwardly away from the stationary wall 11.

A portion of the stationary wall 11 is bent forwardly so as to provide a supporting ear or lug 25 which is parallel to the end wall 13. Between the end wall 13 and the lug 25 there is pivotally mounted a movable gate 26. The gate 26 preferably has an inwardly extending portion 27 which comprises the base of an inclined coin runway. Preferably the gate 26 is provided with a coin testing device comprising a weight testing cradle 28 pivotally mounted at 29 and having a counterbalance 31. The cradle 28 has an arcuate configuration 32 which is slightly smaller than the arcuate configuration of the periphery of a coin of the proper denomination. This arcuate configuration 32 serves to prevent over diameter coins from passing the over diameter stop subsequently to be described. This curvature also prevents the cradle from tilting sufficiently when the coin is under diameter. An under diameter coin will not have the center of its weight located properly with respect to the counterbalance 31 so that the cradle does not discharge the coin into the coin runway. Only when the coin is of proper diameter and of a weight at least equal to the proper weight will the center of weight be sufficiently to the right as seen in Fig. 1 and of sufficient magnitude so that the cradle will be pivoted so as to discharge the coin thereon into the coin runway. The gate 26 is provided with a stop pin 33 for limiting the downward movement of the cradle 28 so that a coin carried by the cradle is discharged upon the inclined runway formed by the base portion 27 secured to the gate 26.

After the coin has been subjected to the weight test, the coin may be subjected to an over diameter test so that a coin of proper weight when pivoted by the cradle 28 must clear an over diameter stop 34 which is formed by an inwardly projecting lug adjacent the top edge of the movable wall 14. Assuming that the coin clears the over diameter stop 34, the coin rolls down the inclined runway 27 to be subjected to the effect of a magnetic field. The magnetic field is formed by a pair of permanent magnets. One permanent magnet 35 is mounted on the outside of the stationary wall 11 so that its pole pieces 37 extend through suitable apertures in the wall so as to present a flush surface on the inside of the wall 11. Another magnet 36 is mounted on the outside of the movable wall 14 with the pole pieces 38 extending through suitable apertures so as to present a flush surface on the inside of the movable wall 14. The coin rolling down the inclined runway 27 will be stopped by the action of these magnets if the coin is a magnetic slug. If the coin is not of paramagnetic material, the coin will continue on in a free trajectory. The coin will have a trajectory so as to strike an anvil 39. An acceptable coin rebounds from the anvil 39 to clear a barrier 41 which serves as a segregation member between the acceptance

chute and the reject chute. As seen in Figure 3 the reject chute is to the right of the barrier 41, and the acceptance chute is to the left of the barrier.

The anvil 39 is shown in detail in Figure 5 and is mounted on the stationary wall 11 by a screw or bolt 42. The anvil 39 consists of a relatively thin sheet of hardened metal so as to present a substantially knife edge surface to the rim of the coin. The anvil 39 is spaced from the wall 11 by a washer 43 of such thickness that the knife edge surface 39 is located substantially midway between the stationary wall 11 and the movable wall 14. If desired a suitable slot 44 may be formed in the wall 11 to provide a certain degree of adjustment of the height of the anvil 39 so that the desired rebound trajectory may be obtained to cause an acceptable coin to pass into the acceptance chute to the left of the segregation barrier 41. Where such construction is employed the anvil 39 may have a trapezoidal shape so that the right end portion bears against the end wall 12 to insure rigidity and maintenance of the contact surface at a constant angle for any position of adjustment. The wall 11 may also be provided with an adjustment slot 45 so that the segregation barrier 41 may be moved within certain limits. The barrier 41 may be secured in position by a suitable bolt or screw 46.

The wall 11 at a point just below the gate 26 is provided with an inwardly struck deflector 47 which cooperates with an inwardly formed deflector 48 on the movable wall 14. The gate 26 is arranged to be moved outwardly for clearing the coin passage of any coins blocking the passage either due to being under weight or over diameter. Such coins then fall down on to the deflector 47 and engage the cooperating deflector 48 to drop into a chute 49 which connects with the reject chute or outlet.

In order to provide for clearing the coin selector of magnetic slugs, over diameter coins and under diameter coins, there is provided a scavenger lever 51 which is pivotally mounted on a pin or stud 52 on the back side of the stationary wall 11. The lever 51 is provided with a finger actuating portion 53 which may be moved by the finger or by a rod or other mechanism which is manually actuated for clearing the coin selector. The lever 51 is biased to an upward position by a spring 54 which passes about the stud 52 and has one end in engagement with the stud pin 55. The other end of the spring 54 engages an outward projection 56 on the arm 51.

In order to clear the faces of the pole pieces 37 and 38 of the magnets 35 and 36 respectively there is provided a scavenger arm 57 which is pivotally mounted on a stud 58. The scavenger arm 57 is mounted on the wall 11 between the walls 11 and 14 so as normally to be in a position some distance above the inclined runway formed by the base member 27 of the gate 26. The arm 57 has a bell crank configuration carrying at one end a pin 59. The pin 59 passes through a slot 61 in the lever 51 at a point intermediate the ends of the lever. At a point intermediate the pins 52 and 59, the lever 51 is provided with a cut out portion 62 which engages a finger or arm 63 forming an integral part of the gate 26. In the position shown in Figures 1 and 3 the scavenger lever 51 is in a substantially horizontal position. In that position the finger 63 is in a position so that the gate 26 hangs in a substantially vertical plane. In such position the inner edge of the

inclined runway base 27 is in contact with the inner surface of the stationary wall 11 so that the weight testing device or cradle 28 is in a plane parallel to the wall 11. When, however, the scavenger lever 51 is actuated in a downward direction, the notch 62 moves the lever 63 downwardly to swing the gate 26 outwardly. At the same time the pin 59 actuates the scavenger arm 57 so that it sweeps across the faces of the permanent magnets to move any slug held thereby toward the reject chute via the deflectors 47 and 48. If an over diameter coin or an under diameter coin is retained in position by the gate 26, the outward movement of the gate releases such coin so that it strikes the deflectors 47 and 48 and passes into the reject chute 49.

It may then be assumed that the coin selector has its parts generally in the position shown in Figure 1 and that it is desired to open the selector for cleaning the interior surfaces. The service operator grasps the finger portion 24 of the latch 23 and moves it upwardly so as to disengage the latch from the strike 22. The entire movable wall 14 may then be moved outwardly to a position substantially that shown in Figure 3. The service man may then take hold of the bottom of the gate 26 and move it through an angle of at least 180° to a position substantially that shown in Figure 3. With the gate 26 and the wall 14 in the position shown, it comes apparent that all surfaces may readily be cleaned with a brush and detergent. Thus all foreign matter, dust, oil and grime may be removed, and the pivotal connections for the movable parts of the weight test device and the scavenger mechanism may be lubricated. Opening up the inner surfaces of the coin selector also makes it possible to make any necessary adjustments of either the anvil 39 or the segregator 41. After the inner surfaces have all been cleaned and the parts lubricated, the gate and the wall may be restored to their original position whereupon the selector is again ready to function in its proper manner.

The coin selector shown in Figures 1 to 5 utilizes a rebound anvil. Rebound anvils are commonly utilized in segregating acceptable from non-acceptable coins in the nickel or five cent denominations. In selectors particularly designed for the five cent coins, it is also common at times to include a test for washers or perforated coins. Such testing device has not been shown in Figures 1 to 5 but is shown in conjunction with the selector illustrated in Figures 6 to 9. The selector shown in Figures 6 to 9, however, will be described as being applied to testing silver coins such as dimes and quarters.

The coin selector shown in Figures 6 to 9 has a stationary wall 65 and integrally formed end walls 66 and 67. A cooperating movable wall 68 is hingedly connected to the end wall 67. A gate 69 is hingedly supported adjacent the top of the stationary wall 65. The gate 69 is pivotally mounted between the end wall 66 and a projection or ear 71 formed of a portion of the stationary wall 65. The gate 69 is provided with pintle portions 72 and 73. The pivot or pintle portion 73 is appreciably longer than the pivot 72 so that the entire gate 69 may be removed if desired. This is accomplished by supporting the shorter pivot 72 in a suitable aperture in the end wall 66. The gate 69 is biased toward the end wall 66 by a disc spring 74 positioned between the gate 69 and the projecting lug or ear 71. The gate 69 carries a weight testing cradle 75 which has a counterbalancing weight 76 extending through

an aperture 77 in the gate. The cradle 75 is pivotally mounted on a suitable stud 78 and the movement of the cradle is limited in a downward direction by means of a stop stud 79. The gate 69 also has an inwardly projecting portion 81 which serves as the foundation for an inclined runway. When the coin engages the arcuate surface of the cradle 75, and is of at least a predetermined weight and diameter, the cradle 75 will tilt so as to discharge the coin from the cradle on to the inclined runway 81 to subject the coin to subsequent tests. In so doing the coin must however clear an over diameter stop 82 which is formed as an inward projection adjacent the upper edge of the movable wall 68. If the coin is of proper diameter it will roll down the inclined runway 81 so as to be subjected to the influence of the magnetic field produced by a pair of permanent magnets 83 and 84 arranged with pole pieces 85 and 86 extending through suitable apertures in the fixed wall 65 and the movable wall 68 respectively. These magnets affect the trajectories of non-magnetic coins rolling down the inclined runway 81. These magnets serve to retain paramagnetic slugs on the runway or adjacent the faces of the permanent magnets 83 and 84. The end of the runway 81 is arranged for cooperation with an adjustably positioned barrier or segregation member 87 which extends through a suitable aperture 88 in the wall 65. The edge of the projecting member 87 may be adjusted by means of a slot 89 formed in the wall 65 and a suitable fastening means or bolt 91 which holds the member 87 in position. The member 87 is provided for engagement by such coins which have a particular reaction to the magnetic field as is the case where copper coins are inserted in the coin selector. Copper coins are slowed down by the magnetic field to a much greater extent than are silver coins with the result that the copper coins just roll over the edge of the inclined runway 81 and thereupon strike the upper edge of the segregating barrier 87. This causes the coin to be thrown outwardly so as to strike a separator or barrier 92. This barrier is pivotally mounted at 93 and has a rearwardly extending portion 94 of sufficient mass as to normally retain the forward projection 92 in the position shown in Figure 6. The segregator portion 92 extends through an aperture 95 in the rear wall 65. The segregator or barrier 92 is mounted so as to be capable of slight pivotal movement upon receiving the impact of a coin thereby to prevent undue rebound of the coin. A copper slug will strike the member 92 and drop toward the right into the reject opening.

The silver coin will leave the end of the inclined passageway 81 and strike the separator 92 so as to cause the coin to move to the left in Figure 6 and pass down the separator 96 into the acceptance chute. An exact position of the member 92 within the opening 95 may be varied within certain limits by means of the mounting member 97 which is longitudinally adjustable by virtue of an adjustment slot 98 formed in the stationary wall 65. A suitable bolt 99 is provided for retaining the segregating member 92 in adjusted position.

The movable wall 68 carries on the outside a reject passage 101 for receiving coins which are rejected due to a scavenging action on the coin selector. The wall 68 adjacent the chute 101 is provided with an inwardly curved deflector portion 102 which is adapted to extend into a

longitudinal opening or recess 103 in the fixed wall 65. Thus when the gate 69 is moved outwardly to release any coins held thereby, the coins will drop down to engage the deflector 102 and drop into the reject runway 101.

The coin selector wall 68 is pivotally mounted on the end wall 67 so that if desired the wall 68 may be removed entirely. To this end the wall 68 in the proximity of the wall 67 is provided with a laterally bent end portion 68a having formed at opposite ends pivot members 104 and 105, the latter one being longer. Interposed between the upper end of the portion 68a and an inwardly turned ear portion 106 of the end wall 67 is a disc spring retaining member 107. The end wall 67 has a cooperating lower ear 108 struck inwardly and formed with a suitable aperture for receiving the lower pivot member 104. If it is desired to entirely remove the movable wall 68, a movement upwardly to compress the spring 107 will permit disengagement of the pivot member 104 from the apertured ear 108. Since the lower edge of the gate 69 extends beneath the upper edge of the deflector 102, the gate 69 must be at least partially raised before the shiftable wall 68 can be moved to open position. After removal of the pivot 104 the movable wall 68 may be tilted and moved downwardly so as to withdraw the pivot 105 from the apertured ear 106. Thus if desired the entire wall may be removed for cleaning and for servicing.

If desired the coin selector may also be provided with a means for stopping apertured coins. Such an arrangement may be optional with coins of a denomination commonly found in silver coins, but it is more commonly found in conjunction with five cent coins. This washer stopping means comprises a lever 109 supported from an outwardly extending ear 111 from the wall 65. The lower portion of the lever 109 is bent inwardly so as to have a small projecting portion 112 adapted to pass through an aperture 113 in the wall 65. The aperture 113 is located so as to be in the coin passageway formed by the pivoted gate 69. It will be noted that the lower extremity of the lever 109 has an inclined surface portion 114 which is adapted to be engaged by a scavenger arm 115. The scavenger arm 115 is provided with a finger or actuating portion 116 at its outer free extremity. The arm 115 is pivotally mounted at the other extremity at 117 and is biased upwardly by means of a spring 118 passing around a pivot support 119. The spring 118 engages a stationary stud 121 on the wall 65 and also engages a projecting ear or arm 122 formed on the scavenger arm 115. When the arm 115 is moved downwardly for scavenging purposes, the surface 114 of the lever 109 is engaged so as to withdraw the projecting pin portion 112 from the aperture 113.

In order to remove magnetic slugs which may adhere to the pole pieces 85 and 86 of the magnets 83 and 84 there is provided a scavenger sweep lever 123 pivotally mounted at 124 and having a bell crank portion 125 in pivotal engagement with an intermediate part of the scavenger arm 115. This pivotal connection may include the stud 126 which moves in a longitudinal slot 127 in the arm 115. A downward movement of the lever 115 actuates the outer extremity of the sweep arm 123 so as to clear the faces of the magnets and to move the slug over toward the deflector 102 of the movable wall 68.

At an intermediate point between the slot 127 and the pivotal connection 117, the arm 115 is pro-

vided with a notch 128 which is adapted to engage an arm 129 integrally formed with the gate 69. A downward movement of the lever 115 therefore actuates the arm 129 to cause the gate 69 to be swung outwardly. The weight cradle 75 has such configuration as to stop any coins which are under weight or under diameter. Either type of coin will fail to move the counterbalancing weight 76 sufficiently to permit the coin to be discharged on to the runway 81. When the gate 69 therefore is moved outwardly in the scavenging action, the coins are permitted to drop on to the deflector 102 and to roll down the discharge or reject chute 101.

The movable wall 68 is normally retained in a position parallel to the wall 65. In order to provide proper cooperation between the components on the wall 68 and the wall 65, there is provided in the wall 68 a guide notch 131 which cooperates with a guide projection 132 which is formed in the end wall 66. Another notch 133 is provided for passage beyond the latch portion 134 which is also formed in the wall 66. A pivoted latching member 135 is pivotally mounted at 136 and biased in one direction by means of a spring 137. The latch 136 is of bell crank configuration having a finger actuating portion 138. Movement of the latch 135 by grasping the finger portion 138 will be in opposition to the spring 137 to disengage the lower latching portion 139 from the latched strike 134. Thus the latch mechanism described may be actuated to permit the wall 68 to be moved outwardly for cleaning purposes.

The pivoted gate 69 may be grasped and moved upwardly to the position shown in Figure 8. If desired the entire gate may be removed by compressing the spring 74 so that the pivot 71 may be withdrawn from the aperture at the end wall 66. When this has been accomplished the gate 69 may be tilted so as to withdraw the pivot 73 from the ear or supporting bracket 71.

Cooperating with the guide portions 131 and 132 and the latch mechanism for retaining in position the movable wall 68, there is provided an adjustable stop 141 mounted in a threaded aperture in the wall 65. A lock nut 142 is provided to retain in adjustment the stop screw 141 so that the end of the stop screw abuts the inner surface of the movable wall 68 to insure the proper spacing between that wall and the stationary wall 65.

From the foregoing disclosure of two embodiments of the present invention, it becomes apparent that for any denomination of coin, there has been provided a novel coin selector structure which permits ready access to all the interior surfaces of the selector for cleaning and adjusting purposes. For all denomination coins, a unique weight testing cradle structure has been provided which serves to block under weight and under diameter coins and which in cooperation with an over diameter stop serves to block over diameter coins. For testing coins of five cent denomination, there has been disclosed a unique rebound anvil showing a knife edge to the rim of the coin. A coin selector designed for the five cent coins may incorporate the washer stop mechanism shown in the second embodiment.

For the testing of silver coins such as ten and twenty-five cent coins, a series of tests are employed including the adjustably positioned segregator immediately beneath the inclined runway and the pivotally mounted segregator immediately above the acceptance and reject chutes

which by virtue of its pivotal mounting eliminates spurious action due to a rebound of a coin striking this segregator. Coin selectors for all denominations of coins may be so constructed as to have the gate and the movable wall removable as disclosed in the embodiment illustrated in the drawings, Figures 6 to 9.

It will also be appreciated that while the drawings have shown several specific embodiments and certain details that the present invention is not to be limited thereby since such variations in the arrangements and in the individual details are contemplated as may be commensurate with the spirit and scope of the invention expressed in the following claims.

This invention is hereby claimed as follows:

1. A coin selector comprising a stationary wall having a pivoted gate provided with a member to form an inclined runway, said gate defining a coin passageway adjacent the entrance to said selector, said gate being mounted by a separable hinge normally retained in hinged relation by a spring, said gate being provided with a coin testing means for stopping under diameter, and under weight coins, said gate being pivotally mounted for manual movement away from said wall to clear said testing means of stopped coins and to provide access to the inner surfaces of said gate and said wall.

2. A coin testing device comprising in combination a frame having a vertical wall forming one wall of a coin passageway, an entrance chute formed by a gate pivotally mounted on said wall, said gate carrying a coin testing device for stopping under diameter and under weight coins, said testing device comprising a pivotally mounted counterbalanced lever having a coin receiving surface of a configuration generally complementary to the outer periphery of a coin.

3. A coin testing device comprising in combi-

nation a frame having a vertical wall forming one wall of a coin passageway, an entrance chute formed by a gate hingedly mounted on said wall, said gate carrying a coin testing device and a part of the base of an inclined runway, said testing device comprising a pivotally mounted counterbalanced lever normally positioned so as to intercept coins introduced into said chute, said device in response to a coin of at least a predetermined weight and size operating to pivotally move to discharge said coin on said runway, abutment means positioned above the coin passage formed by said runway for cooperation with said testing device for stopping over diameter coins, said testing device having a coin engaging surface generally complementary to an arcuate portion of the periphery of a coin, said surface be so positioned relative to the abutment means as to stop over diameter coins.

20 4. A coin testing device as claimed in claim 3, wherein the abutment means is carried by a movable wall substantially co-mating along adjacent edges with said gate when closed and wherein said movable wall is hingedly connected to the vertical wall and is provided with a reject chute for receiving rejected over-diameter coins stopped by said abutment means.
